UNITED STATES PATENT OFFICE.

HARRY S. LEE, OF PLYMOUTH, MICHIGAN.

THERMOSTATIC CORE CENTRALIZER.

Application filed January 8, 1925. Serial No. 1,166.

To all whom it may concern:

Be it known, that I, HARRY S. LEE, a citizen of the United States, residing at Plymouth, in the county of Wayne and State of Michigan, have invented certain new and useful Improvements in Thermostatic Core Centralizers, of which the following is a specification.

This invention relates to permanent moulds, and has for its object the provision of a thermo-responsive compensating device calculated to take up the clearance which must necessarily occur between the core and the mould sections where the core is supported by the mould sections.

In permanent moulds, the mould sections are made ordinarily of metals which will have some expansion when they become heated. This will, therefore, leave a slight clearance between the core and the mould, and will permit the core to shift in the mould, thereby resulting in an imperfect casting. It is the object of the present invention to provide thermo-responsive members which will automatically compensate for such expansion and take up the clearance which would otherwise occur between the core and the mould sections.

In my co-pending application, Serial No. 1,168 the generic invention is claimed and the specific mechanical devices for permanently taking up the clearance, and in my co-pending application, Serial No. 1,167 another type of mechanical device is claimed which operates automatically to take up the clearance. The present application is confined to an automatic device that is calculated to take up this clearance, both automatically and in accordance with thermo-conditions existing in the mould.

In the drawings:

Fig. 1 is a plan view (fragmentary in character) showing a mould equipped with my thermo-responsive compensating device.

Fig. 2 is a section taken on the line 2-2 of Fig. 1.

Fig. 3 is a section taken on the line 3-3 of Fig. 2.

Fig. 4 is a plan view of the modified form of compensating device.

Fig. 5 is a section taken on the line 5-5 of Fig. 4.

Fig. 6 is a section taken on the line 6-6 of Fig. 5.

Figs. 7 to 13 inclusive are similar views of modified forms of construction, the sec-

tion lines in the several views indicating where the view of the same number is taken.

Figs. 15 and 16 are views of further modified construction.

60
a and *b* represent two sections of a split mould. These sections are provided with annular grooves *d* and *e* to receive the corresponding ribs *f* and *g* of the core *c* (see Fig. 13). The core is fitted into one section of the mould when the other section has been withdrawn. This will support the core while such other section is replaced. Hence the contact of the core head with the upper part of the mould suspends the core 65
70 in proper relation with respect to the mould. However, when the mould heats up it causes the same to expand slightly and draw away from the core. This leaves the clearance *x* shown in an exaggerated form in Fig. 13. 75
This would permit the core to shift into the mould, were it not for my automatic compensating-device which I am about to describe.

80
In the form shown in Fig. 1 an adjustable abutment *h* is provided by the threaded stud *j* of the jamb nut *i*. Supported against this abutment is a thermo-responsive block *k*. I find that aluminum is a good material for the construction of such a block, but 85
obviously other suitable metals might be provided. The co-efficient of expansion of the aluminum with respect to the cast iron mould is such that the aluminum elongates sufficiently in an inward direction to compensate for the enlargement of the diameter 90
of the mould. This will automatically take up any clearance between the core and the mould. If it is found that unsatisfactory results are secured at any point of the 95
mould the block may be adjusted in or out by loosening the jamb nut *i* and applying the screw driver to the slotted end of the stud *j*. In order to keep the thermostatic block from falling out a key *m* is provided. 100

In the forms shown in Figs. 4, 5 and 6 a spacing block *n* is stressed by a flat bowing type of thermo-responsive element *o*. This is the same action but a different type of element. In Figs. 7, 8 and 9 the thermo-responsive block *p* is supported in place by the pins *q*.

In the forms shown in Figs. 10 and 11 the thermo element is in the form of a headed stud *r*, and in the forms shown in 110
Figs. 12, 13 and 14 the thermo element is in the form of a segment of a ring which

bows out as at *s* when the heat causes the elongation of the ring.

In Figs. 15 and 16 is shown a modified construction in which the sliding blocks 10 is yieldingly forced inwardly by the thermo-responsive spring elements 11. It will be noticed that the elements 11 normally exert a pressure urging the sliding blocks inwardly to centralize the core to take up the clearance between the core and the mould sections when the mould expands. The thermo-responsive element also will exert a further pressure when the temperature of the mould increases, thereby increasing the pressure exerted by the sliding blocks onto the core.

What I claim is:

1. In a permanent mould, the combination of a plurality of mould sections of expandable material, a core supported therein by contact with the mould sections, and a thermally controlled means for taking up the clearance between the core and the mould sections due to the expansion of the mould.

2. In a permanent mould, the combination of a plurality of moulded sections of expandable material, a core supported therein by contact with the mould walls, and thermo-responsive expansion devices for taking up the clearance between the core and the mould due to the expansion of the latter.

3. In a permanent mould, the combination of a plurality of expandable mould sections, a core supported therein by contact with the

mould walls and members supported on the mould sections of thermo-responsive material for compensating for the expansion of the mould walls and for centralizing the core notwithstanding the said expansion. ⁴⁰

4. In a permanent mould, the combination of a plurality of mould sections of expandable material, a core supported in the mould by contact with mould walls, members of thermo-responsive material for compensating for the expansion of the mould and centralizing the core notwithstanding said expansion and adjustable means for altering the position of such members. ⁴⁵

5. In a permanent mould, the combination of a plurality of expandable mould sections, a core supported therein by contact with the mould walls and thermo-responsive devices for taking up clearance between the core and the mould due to the expansion of the latter. ⁵⁰

6. In a permanent mould, the combination of a plurality of expandable mould sections, a core supported therein by contact with the mould walls, sliding spacers supported in the mould sections, and yielding thermo-responsive members urging the spacers onto the core to centralize the core notwithstanding the expansion of the mould sections, whereby an increase in the temperature of the mould sections increases the pressure exerted by said spacers onto the core. ⁶⁰ ⁶⁵

In testimony whereof I have affixed my signature.

HARRY S. LEE.
